UNITED STATES PATENT OFFICE

JOHN SNEED, OF DETROIT, MICHIGAN, ASSIGNOR TO THE MIDLAND STEEL PRODUCTS COMPANY, A CORPORATION OF OHIO

BRAKE

Application filed May 28, 1928. Serial No. 281,062.

This invention relates to vehicle brakes and more particularly to devices for positioning the brake shoe.

It is among the objects of my invention to provide means for quickly and easily adjusting the size and position of the shoe with regard to the brake drum. Another object is to adjust the effective length of the shoe. A further object is to provide adjusting means by which the several brakes in a given vehicle can be quickly and accurately adjusted with exact likeness to the same operative relation to the several drums and other functionally related brake parts. A further object is to provide simple and effective means for adjustably and resiliently centering the unanchored parts of the brake shoe so that uniform clearance may be maintained as the shoe is adjusted and displaced to compensate for wear.

Other objects will appear from the following description of a preferred form of my invention which is shown in the environment of a well known brake of the internal expanding type. A preferred form of my invention is illustrated in the drawings; the essential characteristics are summarized in the claims.

In the drawings, Fig. 1 is an elevation of the brake assembly including the shoe within the drum; Fig. 2 is a vertical section through the upper part of the assembly illustrated in Fig. 1; Fig. 3 is a section taken along the line 3—3 of Fig. 2; Fig. 4 is a section taken along the line 4—4 of Fig. 2; Fig. 5 is a perspective of the adjustor retaining member which is secured to one end of the shoe; Fig. 6 is a section taken along the broken line 6—6 of Fig. 1.

Referring particularly to Fig. 1, the brake assembly consists of a back plate or apron A which carries an anchor pin P and is secured to a relatively fixed part of the vehicle. Brake drum D is secured to the wheel and revolves in the usual manner. The friction element illustrated comprises a substantially annular shoe S carrying the usual brake lining L. The shoe S is of the full floating type and comprises a relatively rigid channel part 1 and a relatively flexible band part 2 which

may be joined together by a butt weld 3. The channeled end of the shoe engages the anchor pin P along the arcuate bearing portions 4 and to the other end of the shoe is adjustably secured a member 10 which engages the anchor pin along the arcuate bearing surfaces 5.

To operate the brake, spreading mechanism in the form of a toggle T which is well known in this type of brake construction has its ends connected to the channeled end of the shoe and to the piece 10. The pivot pin 6 of the toggle may be drawn toward the apron to expand the brake by such means as a cable or floating link, not shown. Brakes are arranged in the vehicle so that the forward movement of the vehicle causes drum rotation as indicated by the arrow and in the usual operation of retarding the vehicle, the member 10 is moved from the anchor carrying the free end of the band part of the shoe into engagement with the drum and swinging the less flexible part of the shoe 1 about the anchor into engagement, the braking torque being taken through the side flanges of the channel along the anchor engaging surfaces 4.

Retractor springs 7 and 8 may be fixed to the apron at adjacent ends and secured to the ends of the shoes to draw these ends against the anchor. The spring 7 may exert a slightly greater tension so that in the usual operation the flexible part of the shoe will be moved from the anchor into engagement with the drum. Centering springs 30 and 31 position the bottom or mid-portion of the shoe in its idle position and are adjustably secured to the apron in a manner to be described below.

Referring also to Figs. 2 to 5 inclusive, I will describe particularly the means for adjusting and changing the total effective length of the shoe. As mentioned above, the member 10 is adjustably connected to the end of the band-like portion 2 of the shoe. As the member 10 is moved away from this part of the shoe, the total effective length of the shoe is increased. The member 10 in addition to having the arcuate bearing portions 5 also has depending ears 11, see also Fig. 1, which carry a pin for engaging the toggle and

has a tail part or piece 12 which is curved and engages the inner side of the band-like portion of the shoe along the extended area as at 13, see also Figs. 3 and 4. The tail piece 12 extends into a drawn cupped member 15, 5 see Figs. 1 and 5, which is secured near the end of the band portion of the shoe by such means as rivets. As shown in Figs. 3 and 4, the tail piece 12 is closely engaged by the wall and bottom of the member 15.

10 Within the member 15 and bearing against its closed end, as at 16, is a coil spring 17 which lies within a cut away part of the tail piece and bears against it as at 18. The spring 15 is held compressed and tends to force the tail piece and the member 10 out of the retaining member 15 to increase the total effective length of the shoe. Thus without other means to prevent it, the spring 17 would force the shoe into engagement with the drum.

15 To hold the adjusting member 10 in a given position with relation to the end of the shoe, the bottom of the cupped retaining member 20 15 is slotted as at 19 so that at least part 25 of its walls may be drawn together to clamp the tail piece 12 between them as shown in Fig. 4. The tail piece 12 is slotted as at 20. A bolt 21, see Figs. 1, 2 and 4, clamps the tail piece in any desired position. To effect adjustment, the bolt 21 is released so that the spring 17 may extend the length of the shoe, then the toggle T is flattened a desired amount to force the adjusting member and the tail piece clockwise, as viewed in Figs. 1 30 and 2. Thereupon the tail piece is clamped between the walls of the member 15, and as the toggle is released the member 10 is drawn back on the anchor and the shoe then clears the drum by a desired amount. The end of 35 the bolt 21 may be slotted as at 22 so that adjustment may be effected by the nut 23 through an aperture in the apron 25. A cover 26 for the aperture may be provided as shown in Fig. 4.

40 In making the adjustment described in the foregoing paragraph it will be seen that the mid-portion of the brake shoe adjacent the welded joint 3 is moved clockwise as viewed in Fig. 1 when the total effective length of the shoe is increased. Under such a circumstance, the spring 30 would be under greater tension than the spring 31, see Figs. 1 and 6, with the result that a greater clearance would be had adjacent the part 1 of the shoe than the 45 part 2 of the shoe. To compensate for this, the adjacent ends of the springs 30 and 31 are secured to a member 32 which may be adjustably positioned with regard to the apron. A bolt 33 carries the member 32 and passes 50 through a slot 34 in the apron so that the member 32 may be shifted as viewed in Fig. 1 and adjustably secured in any desired position by the bolt 33. The springs 30 and 31 are secured at their far ends to the shoe and 55 extend at an angle to the apron and draw

the shoe toward the apron against indented portions 40 in the apron, see Figs. 1 and 6. In this manner the mid-portion of the shoe is centered and the whole shoe is held out of contact with the drum in idle position. The edge of the shoe is drawn against the indents 40 in the apron. The indents 40 are spaced apart so that the shoe is held against oscillating about a vertical axis and rattling in idle position. The bolt 33 is spaced below a chord which joins the remote ends of the springs both to give the springs better mechanical advantage in centering the shoe and to exert forces more nearly to the curvature of the shoe so that the springs 30 and 31 will not tend to raise or lower the shoe from the anchor.

70 The foregoing is a description of a preferred form of my invention. While modifications within its scope will occur to those skilled in the art, I do not care to be limited other than by the claims appended hereto.

75 I claim:—

1. A brake shoe having a thrust member at one end, and a spring acting between the shoe and said member and tending to force the member beyond the end of the shoe.

80 2. A brake shoe having a thrust member adjustably secured thereto, means urging said member for movement relative to said shoe and means for clamping said member in fixed position.

85 3. The combination of a brake shoe, a separate thrust member associated with the shoe, a normally compressed spring acting between the member and the shoe and means for holding said member and said shoe in relatively fixed position against the force of said spring.

90 4. The combination of a friction device, a thrust member at one end thereof, a normally compressed spring acting between the member and the shoe and means for holding said member and said shoe in relatively fixed position against the force of said spring.

95 5. In a brake, the combination of an expanding device, a shoe, a separate thrust member associated with the end of the shoe and engaging said expanding device, and a normally compressed spring acting between said member and said shoe.

100 6. In a brake, the combination of an anchor, a shoe anchorable at least at one end, a separate thrust member associated with the end of the shoe and engaging the anchor, and a normally compressed spring acting between said member and said shoe and tending to force the shoe away from the anchor.

105 7. In a brake, the combination of a shoe, a member adjustably secured to the end of the shoe, means engaging said member for forcing the shoe against the drum, said member being positionable with relation to the shoe by the pressure exerted by said means when the shoe is forced into engagement with the

drum, and means for holding said member and said shoe in fixed relation while it is forced into a given position by the said means.

8. In a brake, the combination of a shoe, a member adjustably secured to the end of the shoe, means engaging said member for forcing the shoe against the drum, said member being positionable with relation to the shoe by the pressure exerted by the said means when the shoe is forced into engagement with the drum and means for holding said member and said shoe in fixed relation including a cupped part secured to the end of the shoe whose walls frictionally engage said member.

9. In a brake, the combination of a shoe, a separate thrust member carried by the shoe, an anchor and an expanding device both engageable with said member and a normally compressed spring acting between said member and said shoe tending to move said member longitudinally of the shoe.

10. In a brake, the combination of a shoe, an adjusting member carried by the shoe, an anchor and an expanding device both engageable with said member, a normally compressed spring acting between said member and said shoe, means for clamping said member in fixed relation with said shoe and for permitting said member to move with relation to the shoe under the influence of said spring or the expanding device, whereby the shoe may be forced from its anchorage and then secured so that when the shoe is permitted to anchor it will have a certain determinable clearance from the drum.

11. In a brake, the combination of a shoe, a separate thrust member engaging a surface of said shoe, a cupped retaining member secured to said shoe and encompassing said thrust member, and resilient means disposed within said retaining member and acting between said retaining member and said thrust member.

12. In a brake, the combination of a shoe having at least a portion comprising an arcuate lining supporting part, a separate member having an arcuate surface engaging said lining supporting part, a cupped retaining part secured to said lining supporting part and encompassing said member, a coil spring disposed within said retaining part and acting between said part and said member and tending to force said member out of said retaining part.

13. In a brake, the combination of a shoe, a separate adjusting member carried by the shoe, and a cupped retaining member secured to said shoe and encompassing said adjusting member, the walls of said retaining member lying adjacent the sides of the adjusting member and being movable toward the adjusting member to clamp it in fixed relation with said shoe.

14. In a brake, the combination of a shoe,

a separate thrust member adjustably secured at one end of the shoe, said member having a part lying adjacent the shoe, and a cupped retaining member secured to the shoe and encompassing said part, said retaining member having side walls extending adjacent the sides of said part and a slotted bottom wall to permit the side walls to be clamped upon said part.

15. In a brake, the combination of a full floating substantially annular shoe anchorable at either end, an anchor disposed between the ends of the shoe and an expanding device disposed adjacent the ends of the shoe, a separate thrust member adjustably secured to one end of the shoe and disposed between that end of the shoe and the anchor and the expanding means, said member having a curved part lying adjacent the shoe, a cupped retaining member secured to the shoe and encompassing said curved part, a coil spring within the retaining member adapted to move the thrust member bodily beyond the end of the shoe, and means for holding said thrust member in fixed position with relation to the end of the shoe.

16. In a brake, the combination of a shoe having at least a portion comprising an arcuate band like lining supporting part, a separate thrust member having an arcuate surface engaging said lining supporting part, a cupped retaining member secured to said lining supporting part and encompassing said thrust member, a coil spring disposed within said retaining member and acting between said retaining member and said thrust member and tending to force said thrust member out of said retaining member, the walls of said retaining member closely fitting the thrust member, and means for clamping said walls upon said thrust member to hold it in fixed relation with said shoe.

17. In a vehicle brake, the combination of a revolving drum, an apron, an anchor carried by the apron, an expanding device adjacent the apron, a full floating substantially annular brake shoe anchorable at either end, retractor springs for the ends of the shoe, one of said springs being heavier than the other and holding the end of the shoe upon the anchor which takes the braking torque when the vehicle is decelerated in forward motion, means resiliently positioning the mid-portion of the shoe remote from the anchor including a plate adjustably secured to the apron and springs connected between said plate and said shoe, means for adjusting the over-all length of the shoe including a separate member associated with the end of the shoe which normally leaves the anchor in braking action during forward motion of the vehicle, said member being resiliently urged beyond the end of the shoe and onto the anchor and being clamped in fixed relation with the end of the shoe.

18. In a brake, the combination of a revolving drum, an apron, an anchor carried by the apron, a substantially annular full floating shoe anchorable at either end, a separate member at one end of the shoe adjustably positioned with relation thereto and engaging the anchor, means for centering the portion of the shoe remote from the anchor and for maintaining clearance between the shoe and the drum when the brake is idle comprising a plate adjustably secured to the apron, and a pair of coil springs having their near ends connected to said plate and their far ends connected to the shoe at spaced points.
19. In a brake, the combination of a revolving drum, an apron, an anchor carried by the apron, a substantially annular full floating shoe having both ends pivotally supported by the anchor when the brake is idle, and means for centering the portion of the shoe remote from the anchor and for maintaining clearance between the shoe and the drum when the brake is idle comprising a plate adjustably secured to the apron, and a pair of coil springs having their near ends connected to said plate and their far ends connected to the shoe at spaced points and being disposed at an angle to the plane of the apron, said apron having raised portions near the points of attachment between said spring and said shoe whereby the edges of the shoe are resiliently urged against said raised portion and whereby the mid-portion of the shoe is resiliently urged to an idle position determined by the position of said plate with relation to said apron.

In testimony whereof, I hereunto affix my signature.

JOHN SNEED.
